UNITED STATES PATENT OFFICE.

JOHN STOERTZENBACH, OF PEEKSKILL, NEW YORK, ASSIGNOR TO WILLIAM M. CRANE COMPANY, OF NEW YORK.

DESIGN FOR A FRAME FOR GAS-FIRES.

SPECIFICATION forming part of Design No. 34,420, dated April 23, 1901.

Application filed April 1, 1901. Serial No. 53,966. Term of patent 7 years.

To all whom it may concern:

Be it known that I, JOHN STOERTZENBACH, a citizen of the United States, residing at Peekskill, in the county of Westchester and State of New York, have invented and produced a new and original Design for a Frame for Gas-Fires, of which the following is a specification, reference being had to the accompanying drawing, forming part hereof.

In the drawing I have shown a front elevation of a frame for gas-fires embodying my design, the features of which are the configuration and ornamentation.

A indicates the base-section, which is rounded at its ends and is formed principally of the open-work scroll ornaments, as shown. The base-section A is surmounted by a front rail B.

C and D indicate the uprights of the frame, which are provided with the symmetrical scroll ornamentation, surmounted by the sphinx-like faces, all in relief.

The top part of the frame is formed of the

sections or panels E and F, of which the upper panel E lies in the plane of the uprights C and D and is coextensive therewith. This panel E is provided with the leaf-and-scroll ornamentation in relief, which is alike on each side of the center of the panel and reversely arranged. The lower panel F is outwardly rounded and curved at its ends and terminates at the inside of the tops of the uprights C and D. This panel is provided at its central portion with a sphinx-like face and at its end portions with reversely-arranged scroll ornaments.

What I claim, and desire to secure by Letters Patent, is—

The design for a frame for gas-fires shown and described.

Signed this 26th day of March, 1901.

JOHN STOERTZENBACH.
